UNITED STATES PATENT OFFICE

ALBERT E. SIERAD, OF NEW YORK, N. Y., ASSIGNOR TO GEORGE W. BUTTON CORPORATION, OF NEW YORK, N. Y., A CORPORATION OF NEW YORK

DESIGN FOR A FACE-POWDER CONTAINER

Application filed November 6, 1930. Serial No. 37,576. Term of patent 7 years.

To all whom it may concern:

Be it known that I, ALBERT E. SIERAD, a citizen of the United States, residing at New York, in the city, county, and State of New York, have invented a new, original, and ornamental Design for a Face-Powder Container, of which the following is a specification, reference being had to the accompanying drawing, forming a part thereof.

In the drawing

Fig. 1 is a perspective view of my new design.

Fig. 2 is a rear view thereof.

I claim:

The ornamental design for a face powder container substantially as shown.

ALBERT E. SIERAD.
